UNITED STATES PATENT OFFICE.

FRANK BOWERS, OF DETROIT, MICHIGAN, ASSIGNOR, BY MESNE ASSIGNMENTS, TO DIAMOND POWER SPECIALTY CORPORATION, OF DETROIT, MICHIGAN, A CORPORATION OF MICHIGAN.

BOILER-TUBE CLEANER.

Application filed November 21, 1918. Serial No. 263,477.

This invention relates to boiler tube cleaners and it relates particularly to power-driven boiler tube cleaners of the rotary steam jet type.

Because of its ready availability, steam is the preferred medium for applying power to a boiler tube cleaner and the most efficient device for employing the steam for this purpose is a small turbine. A difficulty arises, however, from the fact that a steam turbine operates most efficiently at a very high rate of speed, whereas a steam jet boiler tube cleaner must turn quite slowly in order that the steam may have sufficient time to effect cleaning of the boiler tubes, which are successively encountered by the jets.

It is the object of the present invention, therefore, to provide a turbine driven boiler tube cleaner having a compact, simple and efficient reduction gearing between the turbine and the driven member.

A further object is to provide a speed governing device for the turbine and to provide a casing within which the turbine, its governor and the reduction gearing will be housed in a unitary relation.

The invention is disclosed in a preferred form in the accompanying drawing, wherein

Figure 1 is a view in side elevation of a tubular boiler cleaning unit, to which the herein described driving mechanism is applied, said unit being shown mounted in a boiler wall;

Figure 2 is a sectional elevation of the driving mechanism, the section being taken on line 2-2 of Figure 1;

Figure 3 is a cross section showing a planetary reduction gearing, the section being taken on line 3-3 of Figure 2.

In these views the reference character 1 designates the masonry wall of a boiler, and 2 is a tubular steam blower provided at suitably spaced intervals with jet nozzles 3. Said blower is journaled in a bearing 4 mounted in the wall 1 and projects beyond said bearing into a casing 5 exteriorly secured to said wall. A pipe 6 communicates with said casing at the bottom thereof to deliver steam thereto and thence to the blower member 2. A normally closed valve 7 is provided in the pipe 6, the stem of said valve projecting from the casing thereof, as indicated at 7^a. For opening the valve said stem is engaged by an arm 7^b of a bell

crank pivoted upon the valve casing, the other arm 7^c of said bell crank being engaged by the lower extremity of a rod or cable 8 having its upper end attached to a lever 8^a pivoted upon the casing 5. Within said casing a worm wheel 9 is mounted fast upon the blower member 2 and is laterally provided with a segmental cam member 9^a engageable with an extremity of the lever 8^a extending within the casing. When in the rotation of the blower member and the worm wheel carried thereby the cam member 9^a encounters the lever 8^a, the latter is angularly shifted so as to exert an upward pull on the connection 8 and thus rock the bell crank 7^b, 7^c to unseat the valve 7. After the rotation of the parts 2 and 9 has released the lever 8^a from the cam member 9^a, the valve 7 will be free to again assume its normally closed position. Thus when rotation is imparted to the blower member for effecting cleaning of boiler tubes, the supply of steam to said member during the period of rotation is automatically controlled. The circumferential length of the cam segment 9^a will be proportioned according to the angular distance through which the discharge of steam from the blower is required to act.

The worm wheel 9 is engaged by a worm 9^b. Disposed within an upward extension 10 from the casing 5, said worm is mounted upon a shaft 11 which is journaled at one end in the corresponding end wall of the extension 10, while its other end is extended into a casing 12. The casing 12 is provided with a boss 13 which is screw-threaded into the casing 10 and provides a bearing for the shaft 11. The orifice of the extension 10 engaged by the boss 13 is somewhat larger in diameter than the worm 9^b so that the latter may be inserted or removed through said orifice. Within the casing 12 there is mounted fast upon the shaft 11 a spider comprising a pair of oppositely projecting radial arms 14, said arms respectively carrying pins 15 correspondingly projecting parallel to the shaft 11. Upon each of said pins there are journaled a pinion 16 and a gear 17, the same being either integrally or otherwise rigidly connected. The pinions 16 are enmeshed with an annular gear 18 non-rotatably secured to the casing 12 by screws 18^a. The two gears 17 are adapt-

- ed to be driven by a pinion 19 mounted fast upon a shaft 20 aligned with the shaft 11. Upon the shaft 20 is mounted a turbine wheel 21 to which steam is delivered by a pipe 22 and from which steam is exhausted by a pipe 23. Upon the shaft 20 there is also mounted a centrifugal governor comprising a pair of pivotal arms 24 adapted to exert a frictional stress upon a hub 25 proportional to the speed of rotation. Preferably a partition 26 is interposed between the reduction gearing and the turbine wheel 21, said partition being peripherally clamped between the portion of the casing receiving the reduction gearing and the cap portion 27 within which the turbine wheel is located. The portion of the casing receiving the speed governor is formed as a cap member 28 secured to the member 27.
- 20 It is evident that a very considerable reduction of speed will be effected by the step-down gearing above described, the effect being that the turbine wheel may be driven at the high speed requisite for its efficient operation, while the resulting rotation of the blower member will be quite gradual. By mounting the shafts 11 and 20 in alignment and employing the planetary gearing comprised by the pinions 16 and annular gear 18, a very compact step-down transmission is secured.
- 25 The casing 12, since it houses the turbine, governor and reduction gearing in a unitary relation, permits all of said parts to be assembled complete in the factory so that the installation may be effected in a minimum time.

What I claim as my invention, is:

1. The combination with a boiler tube cleaner, of a casing into which an extremity of said cleaner is extended, drive mechanism for the cleaner within said casing, a housing having screw-threaded engagement with said casing, a pair of aligned shafts within said housing, a turbine upon one of said shafts, a speed governor for the turbine upon the same shaft, a planetary drive connection between said shaft and the aligned shaft, and a drive connection between the

latter shaft and the mechanism in said casing.

2. The combination with a rotary boiler tube cleaner and a steam connection therefor, of a housing through which the steam connection is established, a worm and worm wheel within said housing for driving said cleaner, the housing having an opening through which the worm is inserted, and an encased unitary drive mechanism for the worm, the casing thereof having a projection insertable in said opening of the housing, closing said opening and rigidly mounting said casing upon said housing, said drive mechanism including a shaft mounted in said projection and having driving engagement with the worm.

3. In a boiler cleaner apparatus, the combination with a rotary blower unit provided with a cleaning fluid discharge nozzle for discharging a jet of cleaning fluid adjacent parts of the boiler to be cleaned and a steam supply conduit for the blower unit, of a head assembly forming a connection between said conduit and blower unit, said assembly comprising a gear fixed to rotate with the blower unit, a prime mover casing included in said head assembly and forming a unit therewith, a fluid operated relatively high speed prime mover operable within said prime mover casing and reduction gearing carried by the head assembly between the prime mover and said gear for rotating the blower unit at a relatively slow speed affording efficient cleaning of the said boiler parts.

4. The combination with a boiler tube cleaner, of a casing into which an extremity of said cleaner is extended, drive mechanism for the cleaner within said casing, a housing having engagement with said casing, a pair of shafts within said housing, a turbine upon one of said shafts, a drive connection between said shafts, and a drive connection between the other of the shafts and the mechanism in said casing.

In testimony whereof I affix my signature.

FRANK BOWERS.
